UNITED STATES PATENT OFFICE.

CHARLES A. BICKFORD, OF TWIN FALLS, IDAHO.

VENDING MACHINE.

Application filed January 20, 1925. Serial No. 3,618.

To all whom it may concern:

Be it known that I, CHARLES A. BICKFORD, residing at Twin Falls, Idaho, a citizen of the United States, have invented certain new and useful Improvements in Vending Machines, of which the following is a specification.

My invention has for its object the provision of a device or apparatus to be installed 10 or used in stores to facilitate the sale of merchandise both by the avoidance of necessity of handing money to clerks and by introducing the element of entertainment in making sales. My invention consists in whatever is 15 described by or is included within the terms or scope of the appended claims.

In the accompanying drawings:

Figure 1 is a face view of apparatus embodying my invention; 20 Fig. 2 is a view from the back with the back of the casing removed;

Fig. 3 is a detail view in perspective of the indicator rotating mechanism.

Briefly described my invention comprehends an apparatus having a circular dial and a rotating pointer or index for cooperating with the dial to designate by suitable markings on the dial articles of merchandise which are to be delivered to the customer 25 when the index or pointer designates the same, the customer first having deposited in the casing of the apparatus the price of the articles of merchandise and until such price has been so deposited the pointer cannot be 30 actuated. Thus all the articles of merchandise to be sold by the apparatus will have the same price say 25¢ or 10¢ and the element of entertainment will be afforded by uncertainty as to which article of merchandise 35 at the price named the customer will be entitled to, but, of course, always the customer will get value received for his money.

The casing, 10, shown in the drawings is a shallow box, but, of course, the casing may 40 be given any desired form and may be ornamented in any desired way. In the front side of the casing (which may be covered by glass or other transparent material) is exposed through a circular hole, 11, a dial, 12, which at its rim or margin has equi-distant 45 numbers, say one to twenty and arranged in sequence or order or not just as may be desired and upon a chart or table to be used with the apparatus (but not shown in the drawings) is a list of articles of merchandise 50 correspondingly numbered so that when the

pointer or index, 13, designates or points to a particular number on the dial it will be known that the customer is entitled to the article of merchandise similarly numbered. 60 As a convenient way of sub-dividing the dial and making it ornamental or attractive looking there may be as shown in the drawings a five pointed star concentric with the dial whose points reach to the rim of the dial, diamond shape figures between the points and triangular shape figures between each diamond shape figure and the pair of points between which it is situated and the star and the diamond and triangular shape 65 figures may be variously colored. Around the rim of the dial is a circular series of corrugations or teeth, 14, engaged by a light 70 spring finger, 15, projecting from the tip of the index or pointer so as to assure the stoppage of the index over a numbered space of the dial and not at an intermediate point and thereby making it certain that the pointer 75 will always designate some article of merchandise.

The index or pointer is mounted on a shaft, 16, which extends into the casing, and within the latter has fixed to it a disk or wheel, 17. Pivoted at one end within the casing is a lever, 18, that from its pivot, 19, extends across the disk and projects a short distance through a slot in the side wall of the casing, the projecting portion being for the purpose of being grasped by the hand to swing the lever upon its pivot to effect the 80 rotation of the disk and the index or pointer by the means presently described. A coil spring, 20, attached at one end to the lever within the casing and fixed at its other end to a stationary point in the casing returns 85 the lever to the position from which it is movable by hand, when the lever is released. On the side of the lever next the disk is attached an elastically flexible disk engaging 90 and rotating device which consists of a pair of spring wires, 21, attached at their ends furthest from the disk to the lever and being free at their other ends which are nearest the disk, the free ends of the wires being bent or flexed when the lever is moved by hand, by engagement with a plate, 22, adjacent the disk and in their path as the lever is swung by hand so that during such movement the free ends of the fingers while being flexed will be kept out of contact 95 with the disk and upon passing beyond said plate will whip or spring into their normal 100 105 110

straight position and in so doing will strike the circumference of the disk and with enough force to partially rotate the disk and the index carried thereby. The periphery or circumference of the disk is coated or covered with a strip of rubber, 23, or other material which will provide a friction surface and which will not cause noise when the spring fingers whip into contact therewith. Said finger flexing plate has a lip or flange, 24, which inclines upward from the point where the spring fingers pass out of engagement with the plate after being flexed so that upon the return movement of 15 the lever by the action of the coil spring the free ends of the fingers will encounter the inclined outer side of said lip and on such return movement be thereby kept from engaging the wheel or disk and causing reverse 20 rotation thereof. The spring fingers are flexed or bent by their contact with said lip so that when they pass out of engagement with the same at the highest point they will spring back to their normal straight position in readiness to pass under said lip on 25 the next ensuing hand operation of the lever, and in such movement they are flexed or bent downward by the lip so that when they pass beyond the lowest point thereof they 30 will swing to their normal straight position and thus engage only the upper side of such lip on the return movement. Between the extremities of the spring fingers they pass through holes or slots in separated lugs, 25, 35 which form fulcra upon which they bend or flex as has been explained.

As has been explained before in order that the lever may be operated by hand to effect the movement of the index or pointer the 40 price of the article must be deposited within the casing. To insure this a coin operated lock is provided for the lever which may be released to free the lever only when the proper coin is inserted through the slot, 26, 45 in the side wall of the casing adjacent the exposed portion of the lever. Any coin operated lock may be used for the purpose.

I contemplate employing in connection with the apparatus a register which will 50 register every coin that is placed in the ma-

chine. I also contemplate providing some entertainment giving device which will be released or set in motion when the coin is inserted, as for example some radio apparatus but I do not consider it necessary to 55 illustrate these things in the drawings.

What I claim is:

1. The combination of an indicating mechanism comprising a rotating pointer and means for rotating the pointer comprising a disk, a to and fro movable disk striking finger capable of being flexed or bent from a normal line and means for flexing and then freeing the free end of said finger when moved in one direction. 65

2. The combination of an indicating mechanism comprising a rotating pointer and means for rotating the pointer comprising a disk, a to and fro movable disk striking finger capable of being flexed or bent from a normal line and means for flexing and then freeing the free end of said finger when moved in one direction, the finger contacting portion of the disk being 70 of cushioning material. 75

3. The combination of an indicating mechanism comprising a rotating pointer and means for rotating the pointer comprising a disk, a to and fro movable disk striking finger capable of being flexed or bent from a normal line and means for flexing and then freeing the free end of said finger when moved in one direction, said finger being 80 of wire. 85

4. The combination of an indicating mechanism comprising a rotating pointer a disk connected with the pointer, an operating lever movable in one direction by hand, an elastic finger attached to the lever with a free end adjacent the disk and a surface adjacent the disk in the path of said free end when the lever is moved by hand to flex such free end and out of contact with which said free end passes after a predetermined extent of movement of the lever such free end at such time striking the disk 90 in a direction to impart rotation thereto. 95

In testimony whereof I hereunto affix my signature.

CHARLES A. BICKFORD.
